UNITED STATES PATENT OFFICE.

FRANKLIN P. HINDS, OF LYNN, AND WILLIAM H. DALTON, OF BOSTON, MASSACHUSETTS; SAID HINDS ASSIGNOR TO GEORGE E. BENNER, OF LOWELL, MASSACHUSETTS.

REVERSIBLE SAD-IRON.

1,109,333.

Specification of Letters Patent. Patented Sept. 1, 1914.

Application filed January 7, 1911. Serial No. 601,454.

To all whom it may concern:

Be it known that we, FRANKLIN P. HINDS and WILLIAM H. DALTON, citizens of the United States, residing at Lynn, county of 5 Essex, State of Massachusetts, and Boston, county of Suffolk, State of Massachusetts, respectively, have invented certain new and useful Improvements in Reversible Sad-Irons, of which the following is a specification.

This invention relates to a reversible sad iron and has for its object to provide a novel reversing mechanism for a sad-iron by which the sad-iron may be reversed to bring either 15 side thereof into operative position.

The device is intended to be used in connection with sad-irons which are provided with means, such as gas or electricity, for keeping them hot while in use. In a reversible sad-iron of this type the upper side 20 thereof is being heated while the lower side is in use, and when the lower side gets too cool for further use, the iron is reversed to bring the heated upper side into operative 25 position and the cooled lower side into position to be heated.

Our improved reversing mechanism is one by which the iron can be readily reversed and held in either position, and is one by 30 which a large and heavy iron can be easily reversed.

In order to give a clear understanding of the invention, we have illustrated herein a selected embodiment thereof without, however, attempting to show all the ways in 35 which the invention may be embodied.

In the drawings Figure 1 is a section of a gas-heated smoothing or sad-iron having our improvements applied thereto; Fig. 2 is a 40 plan view of Fig. 1; Fig. 3 is an end view; Fig. 4 is a sectional view through the mixing chamber taken on substantially the line *a—a*, Fig. 2.

We have shown at 45 a smoothing iron, 45 such as is commonly used in laundries or similar places. This smoothing iron is provided with the two opposed smoothing surfaces 3 and 4, and it is reversibly mounted so as to permit either smoothing surface to 50 be brought into operative position. As herein shown said sad-iron is rotatably mounted upon an iron support 5 which pro-

jects through the iron from one end to the other. We will preferably make the smoothing iron in two parts that are suitably connected by the connecting plates 63, 64 that extend across the ends of the iron, as best shown in Fig. 1. The sides of the iron are partially closed by flanges 61, 62 which project from the top and bottom surfaces of the iron, respectively, as best seen in Fig. 1, and which are slightly separated from each other to form suitable air spaces 65 through which sufficient air passes to support combustion when the iron is heated by a gas 65 flame. For reversing the iron to bring either face into operative position, we have provided the novel reversing mechanism which will now be described.

The iron support 5 is provided with a 70 portion 44 which is situated above the iron and which in the present embodiment of the invention is connected to the support by the U-shaped bend 6. On the portion 44 of this support is journaled a shaft 51, said shaft 75 being rotatably mounted in bearings 49 and 50 carried by the portion 44. This shaft is provided with a handle 52 by which it may be oscillated and a connection is provided between the shaft 51 and the iron 45 where- 80 by in either position of the iron the latter can be reversed by rocking the shaft 51 first in one direction and then in the other. As herein shown, the shaft 51 has connected thereto a U-shaped arm 54 and the arm 54 85 has pivotally connected to its lower end a link 55 which in turn is pivoted to the end of the iron 45 at one side of the center thereof, as at 7.

The above construction is such that by 90 swinging the handle 52 to the right, Fig. 3, the shaft 51 will be turned thereby raising the arm 54 and through the connection 55 swinging the iron 45 into a position at right angles to that shown in Fig. 3, and in thus 95 giving the iron a partial turn the operator will apply sufficient force to the handle 52 so that the momentum of the iron will carry it past the central vertical position. When the iron has been carried past this position, 100 then the operator presses downwardly on the handle 52, thus applying a turning force through the shaft 51, arm 54 and link 55 to bring the iron into its completely reversed

position, in which position the link 55 will have the dotted line position Fig. 3, while the arm 54 and lever 52 are in the full line position. By means of this shaft 51 and connection 54, 55, the operator may reverse the iron by simply swinging the handle 52 to the right Fig. 3 with a quick movement sufficient to carry the iron 45 into and past the vertical position, at which time the operator will swing the handle 53 backwardly into its initial position again which results in completing the reversing movement of the iron 54. This reversing movement can be carried on equally well whether the face 15 3 of the iron or the face 4 is uppermost, for the link 55 will act on the iron to give it its initial turning movement equally well whether it be in the full or dotted line position Fig. 3.

20 To hold the iron locked in its operative position a locking latch 53 is provided which is secured to the end of the portion 44 of the support, said catch 53 being constructed to engage the handle 52 and hold it in the 25 position shown in Fig. 3. The handle is preferably made of resilient material so that by giving it a slight lateral pressure it can be disengaged from the catch 53 when the iron is to be reversed.

30 So far as the construction thus far described is concerned the iron may be heated by any heating medium, such, for instance, as gas or electricity. The iron herein shown is heated by a gas flame and for this purpose the support 5 is provided with burner openings and the portions 44 and 6 thereof constitute a gas conduit through which gas is delivered to the burner openings. Where gas is used some means for mixing the gas 35 with air is necessary to make a proper heating mixture, and in the embodiment herein shown the gas is supplied to the iron through a gas pipe 37 which will be connected to the main gas supply by a flexible connection, not shown, so as to permit free 40 movement of the iron. This pipe 37 is threaded into a connection 40 which is divided into two compartments 41, 42, that have communication with each other 45 through an aperture 43. The compartment 42 is open to the air, as at 420, and it communicates with the end 44 of the supporting pipe. The gas which enters the compartment 41 through the pipe 37 is delivered 50 through the aperture 43 with sufficient velocity to cause a suction to take place in the chamber 42 that draws in a certain amount of air through the opening 420 and the mixture of gas and air passes through 55 the pipe 44, 6 to the burner openings in the support 5. The end of the support 5 is shown as closed by a cap 46. If the iron is electrically heated the connection 44, 6 and 60 5 will be used as a conduit for receiving the 65 wires leading to the heating element.

47 is a sheet metal shield which is secured at one end to the cap 46 and at the other end to the connection 40, and 48 is a handle which is secured to the shield, this handle being a convenient one for manipulating the iron. Between the shield 41 and the cap 46 is a strip A of resilient material which bears against the pointed end B of the iron and serves to prevent the iron from any longitudinal movement on the support 5.

While we have illustrated herein a preferred embodiment of our invention we do not wish to be limited to the constructional features shown.

What we claim as new, and desire to secure by Letters Patent of the United States, is:

1. In a laundry iron, the combination with a support, of a reversible iron pivotally mounted thereon, an iron-reversing arm pivoted to turn about an axis parallel to that of the iron, and a link connecting said arm with the iron at one side of its axis.
2. In a laundry iron, the combination with a support, of a reversible iron pivotally mounted thereon, an iron-reversing arm pivoted mounted above the iron, and a link connecting said arm with the iron at one side of its axis whereby the iron may be reversed by a swinging movement of the arm first in one direction and then in the other.
3. In a laundry iron, the combination with a support, of a reversible iron pivotally mounted thereon, a shaft journaled in said support, an arm carried by the shaft, a link connecting the arm with the iron at one side of its axis, and means to turn the shaft first in one direction and then in the other direction thereby to reverse the iron.
4. In a laundry iron, the combination with an iron support presenting a U-shape, of an iron pivotally mounted on one arm of said support, a pivotally mounted iron-reversing arm on the other arm of said support, and a link connecting said iron-reversing arm with the iron at one side of its axis.
5. In a laundry iron, the combination with an iron support having a U-shape, of an iron pivotally mounted on one arm of said support, a shaft journaled on the other arm of said support, and connections between said shaft and the iron whereby turning movement of the shaft will reverse the iron.
6. In a laundry iron, the combination with an iron support having a U-shape, of an iron pivotally mounted on one arm of said support, a shaft journaled on the other arm of said support, a curved iron-reversing arm connected to the shaft, and a link connecting said curved arm with the iron at one side of its axis.
7. In a laundry iron, the combination

with an iron support in the form of a pipe bent into U-shape, of an iron pivotally mounted on one arm of said support, said arm being provided with burner openings, 5 iron-reversing means sustained by the other arm of said support, and connections for delivering gas to said support.

In witness whereof we have hereunto set our hands, this 28th day of October 1910.

FRANKLIN P. HINDS.
WILLIAM H. DALTON.
